HOUSING FOR EMERGENCY REPORTING CALL BOX

Willis C. Reddick, Corinth, Miss., assignor to International Telephone and Telegraph Corporation, New York, N.Y.

Filed Dec. 8, 1971, Ser. No. 206,237

Term of patent 14 years

Int. Cl. D29—02

U.S. Cl. D72—1 A

FIG. 1

FIG. 2

FIG. 3

FIG. 4

FIG. 5

FIG. 6

FIG. 7

FIG. 1 is a perspective view of a housing for emergency reporting call box showing my new design, the exterior supporting housing being shown in broken lines for illustrative purposes only,

FIG. 2 is a top view thereof,

FIG. 3 is a side view thereof,

FIG. 4 is a front view thereof,

FIG. 5 is an opposite side view thereof,

FIG. 6 is a rear view thereof, and

FIG. 7 is a bottom view thereof.

I claim:

The ornamental design of a housing for emergency reporting call box, substantially as shown and described.
